TRANSPORTABLE REFUSE CONTAINER

Samuel Vincen Bowles, 12039 Branford St.,
Sun Valley, Calif. 91352

Original design application Dec. 9, 1971, Ser. No.
206,592. Divided and this application Mar. 19,
1973, Ser. No. 342,471

Term of patent 14 years

Int. Cl. D12—08

U.S. Cl. D12—98

Fig. 2

Fig. 3

Fig. 4

FIG. 1 is a perspective view of a transportable refuse container showing my new design;

FIG. 2 is a left end elevational view thereof;

FIG. 3 is a side elevational view thereof, viewed from the side opposite from that seen in FIG. 1; and

FIG. 4 is a bottom plan view thereof.

This is a division of my copending application Ser. No. 206,592, filed Dec. 9, 1971, entitled Transportable Refuse Container.

I claim:

The ornamental design for a transportable refuse container, as shown.
